UNITED STATES PATENT OFFICE.

ORVILLE Z. FRAZIER, OF ELKHART, INDIANA, ASSIGNOR OF ONE-HALF TO JAMES F. BOYER, OF ELKHART, INDIANA.

ACETYLENE-GENERATOR.

1,282,800.

Specification of Letters Patent. Patented Oct. 29, 1918.

Application filed May 4, 1918. Serial No. 232,577.

To all whom it may concern:

Be it known that I, ORVILLE Z. FRAZIER, a citizen of the United States, residing at Elkhart, in the county of Elkhart and State 5 of Indiana, have invented certain new and useful Improvements in Acetylene-Generators, of which the following is a specification.

This invention relates to acetylene generators of the automatic type wherein the carbid is intermittently fed to the gas-generator chamber through operating means controlled by the pressure of the gas in the generator chamber. The acetylene generator of the present invention has been designed 10 more particularly for use as a portable generator adapted to be carried on a motor vehicle and to supply gas for either or both of the propulsion and lighting systems of such a vehicle. In the designing of this generator I have had in view its adaptability to coördinate and coöperate with a complete system of propulsive equipment for motor vehicles using acetylene gas for which I have lodged application on an internal combustion engine, Serial No. 208,340, filed December 22, 1917, a fuel control valve for internal combustion engines, Serial No. 211,062, filed January 9, 1918, and a pressure regulator, Serial No. 232,578, filed May 4, 15 20 25 30 35 40 45 50 55 60 65 70 75 80 85 90 95 100 105 110

1918; but it should be understood, of course, that the generator of the present invention is in no wise limited or restricted to use in and as a part of such system, but is capable of independent use in any situation or relation where a generator of this general type can be advantageously employed.

Among the objects of the invention are, to provide a simple and compact gas generator well adapted to be mounted and carried on a motor vehicle, to provide an improved construction of gas-generating chamber designed to resist undue splashing and churning of the contents thereof when the vehicle is in motion on rough roads, to provide an improved means for supplying water to the gas-generating chamber when required, to provide an improved means for extracting air from the gas-generating chamber preliminary to the generation of gas therein, to provide an improved intermittent actuating mechanism for the carbid feed valve responsive to and controlled by the pressure of the gas, and generally to provide a portable acetylene gas generator of a unit type of construction occupying

but little space and capable of economical and safe operation at high pressures.

Other objects and advantages of the invention will be apparent to those skilled in the art as the same becomes better understood by reference to the following detailed description taken in connection with the accompanying drawings which illustrate an approved embodiment of the invention, and in which—

Figure 1 is an elevation, partly broken out and in section, of my improved acetylene generator.

Fig. 2 is a central vertical section on the line 2—2 of Fig. 1.

Fig. 3 is a detail elevation of parts shown at the right of Fig. 2.

Fig. 4 is a detail section on the line 4—4 of Fig. 2.

Referring to the drawings, 10 designates 75 as an entirety a generation tank preferably of the cylindrical form shown, having an opening 11 in its top side, and an inclined drain passage 12 on its lower side closed at its lower end by a plug 13. Within the tank 80 is a central longitudinal wall 14, and a plurality of transverse walls 15 extending from the top of wall 14 approximately to the bottom of the tank, these transverse walls being preferably of increasing length from 85 the center toward the ends of the tank as shown. This division of the generation chamber into a considerable number of relatively small communicating chambers effectively checks undue splashing of the water 90 when a vehicle carrying the generator is driven over rough roads.

Superposed on and secured to the generation tank by screws 16 is a casting comprising a hollow base portion 17, an intermediate or waist portion 18 forming a valve casing, and an upper outwardly flaring portion 19 forming a carbid hopper. In the lower side of the valve casing 18 is a discharge port 20, and journaled in opposite 100 ends of the valve casing is an oscillatory valve 21 adapted, when inverted, to deliver measured charges of carbid through the discharge port 20 into the generation tank 10. On the top of the hopper is a filling neck 105 22 that may be closed and sealed by a lid 23, washer 24, and pivoted clamping bolts 25. The hopper is preferably provided in one end wall thereof with a window 26, through which the height and amount of 110

carbid in the hopper may be readily observed. On one end of the valve 21 is a stem 26 carrying a nut 27 and washer 28 at its outer end, and a spring 29, surrounding the stem 26 and confined endwise between the washer 28 and a washer 30 that bears against the end wall of the valve casing, serves to maintain the correct position of the valve in its bearings. A housing 31 preferably 10 encloses these last named parts.

32 designates a water tank that is secured to one side of the carbide hopper and has in its top wall a filling opening closed by a plug 33. A pipe 34 leads from the bottom 15 of the water tank 32 into one side of the hollow base casting 17 that is open to the generation tank, and in this pipe 34 is a cut-off valve or cock 35. 36 designates another pipe that at one end enters the hollow base casting 17 and at its other end connects by a T-coupling 37 with a pipe line 38 which latter, at its upper end leads to the atmosphere and at its lower end is connected to an air pump 39. In the pipe 36 20 is a manually operable cut-off valve 40 and an outwardly opening check valve 41. 42 designates another pipe that enters the upper end of the water tank 32 and, at its outer end connects by a T-coupling 43 with the 25 pipe 38. In the pipe 42 is a manually operable cut-off valve 44. In the pipe 38, between the T-couplings 37 and 43, is an upwardly opening check valve 45; and in the same pipe, above the T-coupling 43 is a 30 manually operable cut off valve 46.

Referring next to the valve - operating mechanism of the carbide feed, which is automatically controlled by the pressure of the generated gas, on one end wall of the carbide hopper is a gear casing 47 that, in turn, supports a housing 48 for an electric motor 49, the armature shaft 50 of which, through a gear train 51, 52, 53 and 54, turns the valve 21; the gear 54 being secured directly 40 to one end of the valve body. On the outer 45 face of the gear 54 is secured a gear 55 meshing with a slightly larger gear 56 beneath the same and fast on a shaft 57 that is journaled in the outer wall of the gear casing 47. On the outer end of the shaft 57 is an arm 58, the outer end of which is connected to the lower end of a tensile spring 59, the upper end of the latter being anchored at 50 to the motor casing. By reference to 55 Fig. 4 it will be observed that the gear 54, which is secured to the valve 21, is only a half-gear;—that is, it has teeth extending through approximately one half of its periphery. It will further be observed that 60 the teeth on gears 53 and 54 are of rounded form, enabling them to readily pass into and out of mesh with each other as the gears are turned without clashing.

Secured to one side of the hollow base casting 17 is a tubular member 61, from which

leads a pipe 62 through which the gas is led off to a point of use either directly or through a suitable pressure regulator, such as that disclosed in my copending application, Serial No. 232,578, hereinabove referred to. On the outer end of the tubular member 61, and preferably formed as an integral extension thereof, is a cylinder 63, to the outer end of which is secured a cap piece 64 having a bore 65 in axial alinement with the cylinder 63 and also a smaller axial bore 66, in which latter is guided the stem 67 of a piston 68 fitting and operating in the cylinder 63. The compression spring 69 above the piston 68 normally forces the latter down- 75 wardly. Keyed to the stem 67 is a disk 70 of hard rubber or another non-conductor of electricity which carries in its periphery a ring 71 of copper or another conducting material. The disk 70 and its ring 71 are slid- 80 able within the bore 65 of the cap 64; and mounted in the side walls of the cap 64 at opposite points are contact members 72 and 73 suitably insulated from the walls of the cap. 90

74 designates conventionally a source of electric current, such as a dynamo or battery, from one side of which leads a circuit wire 75, containing a manually operable switch 76, to the motor 49. The return wire 77 from the motor leads through contact 72, contact ring 71, contact 73, and wire 78 back to the other side of the generator 74. The circuit is, therefore, closed when the contact ring 71 is engaged with the stationary contacts 72 and 73. 100

The generator is charged and operated substantially as follows: The lid 23 is withdrawn, and the carbide hopper is filled with carbide, and the cap then replaced and tightened to its seat. The plug 33 of the water tank is then removed, and the tank 32 filled with water. The valve 35 is then opened, allowing the water to run into and fill the generation tank to about the level indicated in the drawings, the valve 35 being then closed. The tank 32 is next refilled with water and the plug 33 replaced. Valve 44 is next opened and valve 46 closed, and the pump 39 is then operated to create an air pressure above the water in the tank 32. The valve 44 is then closed to seal the pressure in the water tank, and the valves 40 and 46 are opened, and the pump again operated. In this operation the pump acts to suck air 110 out of the generation tank through pipe 36 and discharge this air through pipe 38 to the atmosphere. In this operation the check valve 45 confines the suction stroke of the pump to the generation tank, and the check valve 41 prevents the air from returning to the generation tank on the inward stroke of the pump piston. The valve 40 is then closed, and the generator is ready for work. 115

The switch 76 having been closed, the mo- 120

125

tor 49 is energized, and, through the gear train 51, 52, 53, 54, rocks the carbid valve 21 through a half revolution; the turning movement of the valve being thus limited by 5 half-gear 54. During this operation, the arm 58 is rocked through about 160° to the point indicated by dotted lines in Fig. 3, thereby placing the spring 59 under tension. The continued idle rotation of the gear 53 10 prevents the return movement of the valve under the influence of spring 59 until the pressure in the generator chamber has arisen to such a point that, acting on the piston 68, it forces the contact ring 71 out of engagement 15 with the stationary contacts 72 and 73, thereby breaking the motor circuit and automatically stopping the motor. This permits the reaction of the spring 59 to restore the valve 21 to upright or carbid receiving position, so that the chamber of the valve is refilled. The motor remains idle until the pressure of gas has fallen sufficiently to again close the circuit, whereupon the described cycle of operations is repeated, and another charge of carbid is deposited in the generation tank.

When it is necessary to refill the generation tank, the sludge is withdrawn by removing the plug 13 and allowing the tank 30 to drain. The valve 35 is then opened, and the air pressure above the water in the tank 32 forces this water down into the generation tank against such gas pressure as may exist in the latter. The water tank is then 35 refilled and the air pressure applied thereto in the manner already described.

As hereinabove stated, this generator has been designed more especially with reference to its adaptability for service on motor 40 vehicles to supply gas for either power or lighting purposes or both. It will be readily seen that the generator possesses a very compact and self-contained character, is automatic in respect to the carbid feed, and, 45 by reason of provision for eliminating air and keeping it out of admixture with the gas, is entirely safe and may be employed to generate very considerable pressures. It will be manifest to those skilled in this art 50 that the details of construction and arrangement may be considerably varied from those shown without involving any departure from the principle of the invention or sacrificing any of the advantages thereof; hence 55 I do not limit the invention to the precise construction herein shown and described but reserve all such variations and modifications as fairly fall within the spirit and purview 60 of the appended claims.

I claim:

1. In an acetylene generator, the combination of a carbid hopper, a generation tank beneath said hopper, an intermittently acting measured-charge feed valve between 65 said hopper and said tank, a motor for ac-

tuating said valve from carbid-receiving to carbid-discharging position, means actuated by the generated gas for deenergizing said motor when the gas pressure rises above a predetermined limit, and automatic means 70 for returning said valve to carbid-receiving position.

2. In an acetylene generator, the combination of a carbid hopper, a generation tank beneath said hopper, a measured-feed carbid valve between said hopper and said tank, an electric motor for actuating said valve from carbid-receiving to carbid-discharging position, means actuated by the generated gas for deenergizing said motor 75 when the gas pressure rises above a predetermined limit, and a spring for returning said valve to carbid-receiving position.

3. In an acetylene generator, the combination of a carbid hopper, a generation tank beneath said hopper, a measured-feed carbid valve between said hopper and said tank, an electric motor for actuating said valve for carbid-receiving to carbid discharging position, means actuated by the generated gas for breaking the circuit of 85 said motor when the gas pressure rises above a predetermined limit, and a spring tensioned by said motor serving to return said valve to carbid-receiving position. 90

4. In an acetylene generator, the combination of a carbid hopper, a generation tank beneath said hopper, a measured-feed carbid valve between said hopper and said tank, an electric motor, a self-arresting 100 transmission from said motor to said valve operative to actuate the latter from carbid-receiving to carbid-discharging position, means actuated by the generated gas for breaking the circuit of said motor when the 10 gas pressure rises above a predetermined limit, and a spring tensioned by said motor serving to return said valve to carbid-receiving position.

5. In an acetylene generator, the combination of a carbid hopper, a generation tank beneath said hopper, an oscillatory measured-feed carbid valve between said hopper and said tank, an electric motor, a self-arresting transmission from said motor to 110 said valve operative to turn the latter to discharge position, means actuated by the generated gas for breaking the circuit of said motor when the gas pressure rises above a predetermined limit, and a spring tensioned by said motor through said transmission and acting, when the motor circuit 115 is broken, to return said valve to carbid-receiving position.

6. In an acetylene generator, the combination of a carbid hopper, a generation tank beneath said hopper, a carbid feed valve between said hopper and said tank, a water tank, a delivery pipe from said water tank to said generation tank, a valve in said pipe, 120 125

means for supplying compressed air above the water in said water tank, and means for exhausting air from said generation tank.

7. In an acetylene generator, the combination of a carbid hopper, a generation tank beneath said hopper, a carbid feed valve between said hopper and said tank, a water tank, a delivery pipe from said water tank to said generation tank, a valve in said pipe, 10 a pipe line open at one end to the atmos-

sphere, a pump connected to the other end of said pipe line, branch pipes connecting said pipe line to said water tank and generation tank respectively, and valves in said pipe line and branch pipes, whereby said pump may supply compressed air above the water in said water tank and may also exhaust air from said generation tank. 15

ORVILLE Z. FRAZIER.
